Edward J. Brooks

UNITED STATES PATENT OFFICE.

EDWARD J. BROOKS, OF EAST ORANGE, NEW JERSEY, ASSIGNOR TO E. J. BROOKS & COMPANY, OF NEW YORK, N. Y.

SEAL.

SPECIFICATION forming part of Letters Patent No. 373,007, dated November 8, 1887.

Application filed September 10, 1887. Serial No. 249,336. (No model.)

To all whom it may concern:

Be it known that I, EDWARD J. BROOKS, a citizen of the United States, and a resident of East Orange, in the State of New Jersey, have 5 invented a new and useful Improvement in Seals, of which the following is a specification.

This invention relates, primarily, to press-fastened metallic seals having recessed seal-disks, such as those set forth in my specifications forming part of United States Patents No. 253,674, dated February 14, 1882, No. 294,576, dated March 4, 1884, and No. 368,126, dated August 9, 1887, particularly the latter; but it may be embodied in any soft-metal seal-disk which is compressed in any way to fasten a wire or cord shackle or the like, and thus to secure a car-door fastening or the like from being opened without detection.

All press-fastened seals depend largely for 20 security on preventing access to those portions of the shackle which are inclosed within the seal-disk or coat directly therewith, and on insuring the detection of attempts to open the seals, or any tampering with them, and particularly with the seal-disk. Such seal-disks as commonly made, being wholly of more or less pure lead, can be cut, bent, and otherwise manipulated, and afterward restored in appearance so as to deceive even experts.

30 Means for preventing the cutting of certain styles of seal-disks or insuring its detection are set forth in my specification forming part of United States Patent No. 321,275, dated June 30, 1885.

35 The present invention consists, generally speaking, in a novel means for preventing any tampering with soft-metal seal-disks by bending as well as by cutting, and for insuring the detection of either at the cursory examination 40 which must in most cases be relied on, such means being applicable to every variety of soft-metal seal-disks, as aforesaid.

This invention consists more particularly, first, in a "soft-metal" seal-disk having hard 45 particles, as of brittle metal, distributed throughout the same, as means for preventing or insuring the detection of cutting and bending either or both; secondly, in the combination, with a shackle-wire, of a soft-metal seal-disk recessed to receive one or both shackle

ends, or loops of the same, sidewise, and provided with hard particles distributed throughout the metal of the seal-disk, whereby the seal-disk and every part thereof is rendered brittle as against bending, so as to prevent releasing and replacing either shackle end, after the seal is fastened, by compressing it in any approved way without so marring the seal-disk by fractures as to insure detection; and, thirdly, in a brittle compressible seal-disk composed of a mixture of soft lead and a hard and brittle alloy of lead and antimony, as hereinafter set forth, as a new article of manufacture.

A sheet of drawings accompanies this specification as part thereof.

Figure 1 of the drawings is a perspective view of a "recessed" seal, illustrating the present invention. Fig. 2 is a like view thereof applied to car-door staples and ready to be pressed. Fig. 3 is a like view of the same 70 pressed. Figs 2^x and 3^x represent magnified cross-sections through the seal-disk, as shown in the respective figures correspondingly numbered. Figs. 4 and 5 are perspective views of another recessed seal, illustrating the same invention. Fig. 5^x represents a cross-section through the pressed seal represented by Fig. 5; and Figs. 6 and 7 are perspective views of two more pressed seals, illustrating different ways of fastening such seals.

Like letters of reference indicate corresponding parts in the several figures.

Each of the seal-disks A B C D represented by the drawings is composed of a soft metal, as lead, represented by *a* in Figs. 2^x, 3^x, and 85 5^x, and hard and brittle particles *b*, the latter preferably of an alloy of lead and antimony in suitable proportions, having its melting-point above that of lead, as in type-metal, for example. The alloy may be cast in convenient 90 forms and crushed, or the particles *b* may be supplied by crushed type, or in any convenient way. These hard particles are mixed with melted lead, with which they readily combine, so as to be distributed throughout the seal-disk in sufficient number to render the same and every part thereof brittle, as against bending and rebending. Consequently the pressed seal-disks represented by Figs. 3, 3^x, 5, 5^x, 6, and 7 cannot be opened by cutting and bend- 100

ing them, so as to remove and replace a shackle end, without detection; nor can their thread-ing-holes *h* nor their recesses *r* be opened by "lifting" the lead, even when the seal-disk is 5 only imperfectly pressed. At the same time the seal-disks may be cast on shackle-wires *W*, as represented, or this may of course be omitted; and the composite metal submits to compression in the seal-press, where the displacement of particles is molecular, so to speak, and the seal-disks may be pressed in any preferred shape, as represented by Figs. 3, 5, 6, and 7, including roller-pressing, as illustrated by the figure last named. The wire *W* may 15 also be of any approved kind. A thin flexible wire is represented in Figs. 1 to 5^x, inclusive.

My detector-wire, with anchoring indentations *i*, patented June 27, 1876, (United States Patent No. 179,260,) is represented in Fig. 6; 20 and my detector-wire with bent-up anchoring enlargements *e*, patented July 3, 1877, (United States Patent No. 192,735,) is represented in Fig. 7.

The recessed seals represented by Figs. 1 to 25 5^x, inclusive, are two of those patented August 9, 1887, and reference is made to said Patent No. 368,126 for a fuller description thereof. The present invention may in like manner be embodied in any other soft-metal seal-disk, 30 and many immaterial modifications will suggest themselves to those skilled in the art. It

is, however, peculiarly important in such "recessed" seals, wherein, unless the seal-disk is very thoroughly pressed, crevices *c* will be left, which in soft lead can be opened so as to 35 release one end of the wire, and the wire and lead can be replaced so as to escape detection. This is effectually prevented by my present invention.

Having thus described my said improvement in seals, I claim as my invention and desire to patent under this specification—

1. In a seal, a soft-metal seal-disk having hard particles, as of brittle metal, distributed throughout the same, substantially as herein 45 specified, for the purpose set forth.

2. The combination, with a shackle-wire, of a soft-metal seal-disk recessed to receive one or both ends of the wire, or loops of the same sidewise, and provided with hard particles distributed throughout the metal of the seal-disk, substantially as herein specified, for the purpose set forth.

3. A brittle compressible seal-disk composed of a mixture of soft lead and an alloy of lead 55 and antimony, in hard and brittle particles, substantially as herein specified, as a new article of manufacture.

EDWARD J. BROOKS.
